UNITED STATES PATENT OFFICE

ROBERT A. CARTER, OF MAYWOOD, ILLINOIS

WALL-PAPER APPLICATOR

Application filed May 9, 1930. Serial No. 450,973.

My invention relates to wall-paper applicators and includes among its objects and advantages the provision of an improved apparatus for applying wall paper.

5 The time honored routine in applying wall paper to a room is to install in the room a pair of trestles and six foot trimming boards or a large table on which the skilled workmen can spread out strips of dry paper and cover them with paste, one at a time. After a strip is thoroughly moistened with paste, he folds it end for end several times. After getting the edges of the folded strip exactly even, he trims, with a straight edge and knife, one edge 10 if the paper is to be lapped, and both edges if the paper is to be "butted." In trimming this second edge lies the great danger of spoiling his work as he must pick up the entire pasted mass and swing it completely around in a 15 manner awkward at best. Then, again adjusting his paper by evening the edges as best he can, which is no easy matter since the paste-soaked paper invariably slides awry in swinging it around, he trims the other edge. The 20 strip can now be transferred to the wall where it is applied a little at a time and simultaneously unfolded. The procedure requires no little skill and exertion on the part of the workman and is, relatively speaking, slow. 25 For the best class of work it is necessary to have the edges of the strips hung in abutment, and only extreme skill and care makes it possible to trim the strips and apply them with such accuracy as to secure an abutting 30 joint that is practically imperceptible to the casual glance.

In attempting to devise a simpler and more effective mode of application, I have endeavored to apply the paper by drawing it from a rolled strip past an instrumentality for applying paste to it, and then onto a wall surface, simultaneously trimming the edges of the strip either before or after the application of the paste. In working with paper of the 40 quality employed for wall covering, I have en-

countered serious difficulty in the foregoing procedure, and proved that a roll of wall paper cannot be put into a tool or device and trimmed, pasted and applied to the wall in the one operation because:

First, there must be tension on the paper at the point of cutting in order to keep the paper straight and taut for trimming. The strength of the strip after the paste is on it is hardly adequate to pull it past the paste-applying means and the cutting means, and ordinary cutting means can hardly work well on dry paper under such slight tension, and will not work at all on the wet paper. I have found it is absolutely impossible to successfully trim wall paper after it has become wet with paste, except in the old fashioned way on a flat surface with a straight edge and trimming knife.

Second, drawing it over a paste roller after it has been trimmed creates an uneven surface of the paste on the roller at both edges of the paper; in other words, the paste at the edges of the paper track grows higher and higher and is bound to slide over and smear up the face of the wall paper at its edges, thereby ruining it. (Wall paper must be hung with a spongy paste. It cannot be hung with a thin liquid.)

Having abandoned attempts along the line indicated, I proceed, according to the present invention, to cover the wall itself with paste and then, with the apparatus disclosed hereinafter, to apply dry paper to the wet wall, trimming both edges of the strip as it leaves the roll, and cutting the strip off at the bottom. I make the first application substantially in final position, and then a few seconds later, after contact with the wall has moistened the paper, I loosen and adjust it to exact registry with adjacent strips and smooth down the edges manually.

In the accompanying drawings, Fig. 1 is an end elevation of an applicator in position to apply paper to a vertical wall. Fig. 2 is

a plan view of the same device. Fig. 3 is an enlarged section on line 3—3 of Fig. 2. Fig. 4 is a partial end elevation of the end opposite to that shown in Fig. 1. Fig. 5 is a detail section on line 5—5 of Fig. 3, showing the knife mounting. Fig. 6 is a detail section on line 6—6 of Fig. 2, showing the edge guides on the applying plate, and Fig. 7 is a fragmentary section as on line 7—7 of Fig. 2, showing the roll support.

The embodiment of apparatus selected for illustration of the invention comprises a roll holder 10 in the form of a cylindrical container slit at 12 to permit a strip of paper to be withdrawn from the roll 14. The strip then passes over a curved trimming plate 16 and over a curved applying plate 18, and is pressed by the edge of the plate 18 or by a smoothing brush in the hands of the operator against the wall surface 20.

The roll 14 is supported inside the holder 10 on a rod 22 carried by heads 24 and 26. One of the heads 24 may be adjustably fastened in place by a set screw 28, and the other head 26 may be shoved into the holder 10 far enough to prevent any longitudinal shifting of the roll 14, and there clamped in position.

For convenience in inserting a roll and getting the end of the strip out past the applying plate 18 in the position of Fig. 3, I prefer to let the slot 12 extend out at one end of the holder 10. The resulting flexibility makes it easy to clamp the head 26 in place by pressing the leaf spring 30 to flatten it enough to hook over the catch 32, after which the release of the manual pressure on the spring will cause it to draw the portions on opposite sides of the slot 12 forcibly together and clamp the head 26 firmly in place. I prefer to provide windows such as 34 in the walls of the holder 10 so that the operator may observe the size and condition of the roll 14 as work proceeds.

The trimming plate 16 is attached at one edge to the holder 10, as at 36, and guides the paper over its convex face. The knives 38 are clamped on the knife supports 40 by clamping plates 42 and screws 44. I provide rubber washers 43 between the plate 42 and the heads of the screws. This makes it possible to clamp the knife tightly enough to cut the paper without slipping, while at the same time the operator is able to shift and adjust it readily without loosening the screws. Even during cutting the resilience of this mounting lets the paper slide up on the knife edge and reduces tearing.

The knife supports are mounted for longitudinal adjustment to get precisely the right width for the strip by means of clamping screws 46 passing through longitudinal elongated slots 48 in the supports. I have illustrated a reinforcement plate 50 riveted to trimming plate 16 to provide additional metal for the screw threads of the screws 46.

By locating the knives in the position shown remote from the roll, I secure accurate trimming because the paper has been drawn far enough to let the tension pull it straight.

To load the applicator the head 26 is withdrawn and the roll slipped in place over the rod 22. I prefer to insert the roll by first cutting or tearing off the corners of the paper at a 45° angle and leaving a central tip projecting, after which the roll may be slipped into position. With this tip unrolled and projecting through the slot 12, it is easily accessible and can be passed on through the clearance between the trimming plate 16 and the applying plate 18 and around under the applying plate 18 ready for operation. The head 26 is then placed in position, the clamp 30 snapped into place, and the device is ready for use.

To assist in guiding the paper straight and true, I provide adjustable edge guides 52, each comprising a U-shaped hook portion extending through a slot 54 near the end of the applying plate 18. The adjustable support for the edge guide comprises the fastening screws 56 passing through elongated slots 58 in the portion of the guide located on the opposite side from the paper.

At the loading end I brace and apply the plates 16 and 18 by an interconnecting strip 60 and a straight brace 62 running back to the holder 10 from the outer end of the strip 60. I also run a brace 64 from the inner end of the strip 60 to the holder 10, and this brace is shown curved outwardly away from the plane of the plate 16 to afford a clearance for inserting the paper. At the other end of the device I employ a duplicate strip 60 and brace 62. At this end the unslotted portion of the holder 10 is sufficiently rigid so that another straight brace 66 provides ample support. Centrally in front of the holder 10 I provide the carrying and operating handle 68 with end braces 70 extending over to approximately opposite points on the holder 10.

In preparing for use of the apparatus disclosed, the roll is inserted as above described, and the knives 38 adjusted with respect to the clamping plate 42 to present clean sharp surfaces to the paper. Thereafter, by means of set screws 46, the line of severance along each edge of the strip may be set with adequate precision, the abutment of the roll 14 with the head 24 determining accurately the position of the roll.

The tapered tip cut on the roll before inserting it in place is now drawn past the plate 18 and torn off across the outer edge 72 of the plate, leaving a square end on the strip. Paste is applied to a sufficient wall area to receive two strips or so, and the end of the strip adjacent the edge 72 may be placed against the wall at one end of the area to be covered by the first strip. Referring to

Fig. 1, the position of the device at the time with respect to the wall may be approximately that of Fig. 1, or the holder 10 may be tipped down almost into contact with the wall. With the device in any position similar to Fig. 1, movement of the device to the other end of the area to be covered will draw out a strip of paper which can be gently pressed against the wet wall with a smoothing brush or otherwise. When the end of the area to be covered is reached, the edge of the plate 18 is pulled to the point where the paper should be severed. By tipping the device up considerably beyond the position of Fig. 1 and canting it at a slight angle, a quick movement will tear the end of the strip straight across at the point 72.

The applicator itself has now performed its functions and may be laid aside. The operator may take hold of the lower end of the applied strip and draw most of it from the wall and smooth it back into contact with the wall, at the same time adjusting the edge of the strip into precise registry with the edge of an adjacent strip. It is preferable to employ a smoothing brush materially shorter than the width of the strip.

All this smoothing and adjusting operation may be done by a reasonably skilled workman in almost less time than it takes time to describe it. The applicator may now be picked up again and a second strip applied.

Repetition of the procedure outlined is all that is necessary to complete the entire papering operation. Joints with windows, door openings, etc., are made by pulling the strip down sufficiently to cover the part of wall pasted and then removing applicator and slicing out with razor blade or trimming knife the superfluous portion of paper which remains unpasted.

It will be obvious that paper may be applied in this way to a ceiling with substantially the same convenience with which it may be applied to a vertical wall, with the parts in positions accurately represented by Fig. 1 rotated 90° in a clockwise direction to bring the wall 20 at the top of the figure.

The procedure I have outlined is simple, and perfect work can be effected because both edges are trimmed straight and even with one long continuous cut and the paper immediately applied to the paste on the wall where it belongs, leaving no slightly lapped edges, referred to by the trade as "wire" edges, or spaces between the edges, referred to by the trade as "holidays." Wire edges are common in present day paper hanging, and lapped wall paper is ugly and uncalled for.

Without further elaboration, the foregoing will so fully explain my invention that others may, by applying knowledge current at the time of application, readily adapt the same for use under various conditions of service.

I claim:

1. An applicator for wall paper, comprising a slotted roll holder, a trimming plate positioned to guide a strip of paper drawn through said slot, adjustable knives mounted near the ends of said trimming plate to trim the edges of said strip, and an applying plate positioned to receive the paper after it leaves said trimming plate and guide said paper into contact with a wall surface. 75

2. An applicator for wall paper, comprising a slotted roll holder, a curved trimming plate positioned to guide a strip of paper drawn through said slot over its convex face, knives mounted near the ends of said trimming plate to trim the edges of said strip, and a curved applying plate positioned to receive the paper after it leaves said trimming plate and guide said paper into contact with a wall surface. 85

3. An applicator for wall paper, comprising a slotted roll holder, a curved trimming plate positioned to guide a strip of paper drawn through said slot over its convex face, knives mounted near the ends of said trimming plate to trim the edges of said strip, and a curved applying plate positioned to receive the paper after it leaves said trimming plate and guide said paper over the convex face thereof, said trimming and applying plates having their convex faces facing in opposite directions. 95

4. An applicator for wall paper, comprising a slotted roll holder, a curved plate means positioned to guide a strip of paper drawn through said slot over a convex face and into contact with a wall surface, and knives mounted on said plate means to trim the edges of said strip after it leaves the roll and is under tension to hold it straight but before it engages the wall. 100

5. An applicator for wall paper comprising a slotted roll holder, a curved trimming plate positioned to guide a strip of paper drawn through said slot over its convex face, adjustable knives mounted near the ends of said trimming plate to trim the edges of said strip, a curved applying plate positioned to receive the paper after it leaves said trimming plate and guide said paper over the convex face thereof, said trimming and applying plates having their convex faces facing in opposite directions, and adjustable edge guides carried by said applying plate, the edge of said applying plate being sharp for severing the strip, said roll holder having cut away portions to permit the operator to observe the roll inside. 115 120

6. An applicator for wall paper, comprising a slotted roll holder, a curved trimming plate positioned to guide a strip of paper drawn through said slot over its convex face, adjustable knives mounted near the ends of said trimming plate to trim the edges of said strip, a curved applying plate positioned to 125 130

receive the paper after it leaves said trimming plate and guide said paper over the convex face thereof, said trimming and applying plates having their convex faces facing in opposite directions, and adjustable edge guides carried by said applying plate, the edge of said applying plate being sharp for severing the strip, said roll holder having cut away portions to permit the operator to observe the roll inside, said slot being open at one end to permit insertion of a roll of paper in partially unrolled condition.

In testimony whereof I hereunto affix my signature.

ROBERT A. CARTER.
